C. B. FRALEY & H. STEINES,
BED FABRIC,
APPLICATION FILED JULY 30, 1917.

1,263,659.

Patented Apr. 23, 1918.

UNITED STATES PATENT OFFICE.

CHARLES B. FRALEY AND HENRY STEINES, OF ST. PAUL, MINNESOTA, ASSIGNEES TO
THE UNITED STATES BEDDING COMPANY, OF ST. PAUL, MINNESOTA, A CORPORA-
TION OF MINNESOTA.

BED FABRIC.

1,263,659.

Specification of Letters Patent. Patented Apr. 23, 1918.

Application filed July 30, 1917. Serial No. 183,592.

To all whom it may concern:

Be it known that we, CHARLES B. FRALEY and HENRY STEINES, citizens of the United States, residing at St. Paul, in the county of Ramsey and State of Minnesota, have invented certain new and useful Improvements in Bed Fabrics, of which the following is a specification, reference being had to the accompanying drawings.

10 This invention relates to certain improvements in bed fabrics and it is an object of the invention to provide a device of this general character having novel and improved means whereby the tension of the 15 fabric may be readily and conveniently regulated.

The invention consists in the details of construction and in the combination and arrangement of the several parts of our improved bed fabric wherein certain important advantages are attained and the device rendered simpler, less expensive and otherwise more convenient and advantageous for use, as will be hereinafter more fully set forth.

The novel features of our invention will hereinafter be definitely claimed.

In order that our invention may be the better understood we will now proceed to 30 describe the same with reference to the accompanying drawings wherein—

Figure 1 is a fragmentary view in top plan illustrating a frame having secured thereto a fabric constructed in accordance 35 with an embodiment of our invention;

Fig. 2 is a sectional view taken substantially on the line 2—2 of Fig. 1; and

Fig. 3 is a sectional view taken substantially on the line 3—3 of Fig 1.

40 As herein disclosed 1 denotes the end bar of a frame having engaged therewith the coil springs 2. The inner end portion of the springs 2 are operatively engaged with the metallic straps or slats 3 and each side 45 strap 3 is of increased width and has preferably two springs 2 interposed therebetween and the end bar 1. It is to be understood that the opposite end portions of the straps or slats 3 are similarly connected to 50 a second end bar. Intermediate the straps or slats 3 the end bar 1 has secured thereto a second series of coil springs 4. Each of the springs 4 is provided at its inner end

with an eye member 5 through which is threaded a cable 6 preferably formed of 55 metallic strands. The cable 6 is doubled upon itself and is substantially contiguous and co-acts with the opposite end bar in a manner as has been set forth relative to the springs 4.

At predetermined points longitudinally of the frame the adjacent strands of contiguous cables are disposed through the rigid loops 7 of a length less than the distance between adjacent springs 4. The outer strand of a 65 side cable is connected to the side slat 3 through the medium of the coil springs 8 in alinement with the loops 7. The loops 7 also have directed therethrough the slat 3 positioned between adjacent cables 6. 70

The strands of each of the cables 6 are also threaded through the sleeves 9 which snugly receive the strands. A sleeve 9 is positioned at opposite sides of each of the loops 7 and a pair of said sleeves 9 are movable relative to each of the loops 7. It is thought to be self evident that upon a sleeve 9 at opposite sides of a loop 7 being moved in a direction toward the loop the tension of the fabric will be increased while movement of the sleeves in an opposite direction serves to relieve the tension of the fabric. 80

From the foregoing description, it is thought to be obvious that a bed fabric constructed in accordance with our invention 85 is particularly well adapted for use by reason of the convenience and facility with which it may be assembled and operated and it will also be obvious that our invention is susceptible of some change and modification without materially departing from the principle and spirit thereof and for this reason we do not wish to be understood as limiting ourselves to the precise arrangement and formation of the several parts 90 herein shown in carrying out our invention in practice except as hereinafter claimed. 95

We claim:

A bed fabric comprising a plurality of pairs of flexible strands secured at opposed 100 points, members connecting adjacent strands of contiguous pairs, said members being of a length less than the distance between the points of connection between contiguous strands of adjacent pairs, sleeves coacting 105 with each pair of strands and snugly receiv-

ing the same and positioned adjacent opposite sides of a connecting member, said sleeves being movable toward and from the member, each of said connecting members comprising a loop through which adjacent strands of contiguous pairs are directed and yieldably supported slats interposed between

contiguous pairs of strands and passing through the loops.

In testimony whereof we hereunto affix our signatures.

CHARLES B. FRALEY.
HENRY STEINES.
